ATTORNEY

UNITED STATES PATENT OFFICE.

FREDERICK E. PRÉTAT, OF WATERBURY, CONNECTICUT, ASSIGNOR TO THE ROGERS & HAMILTON COMPANY, OF SAME PLACE.

DESIGN FOR A SPOON.

SPECIFICATION forming part of Design No. 24,353, dated June 4, 1895.

Application filed February 13, 1895. Serial No. 538,290. Term of patent 14 years.

To all whom it may concern:

Be it known that I, FREDERICK E. PRÉTAT, a citizen of the United States, residing at Waterbury, in the county of New Haven and State of Connecticut, have invented and produced a new and original Design for Handles for Spoons and Similar Articles; and I do hereby declare the following to be a full, clear, and exact description of the invention, such as will enable others skilled in the art to which it appertains to make and use the same.

Referring to the accompanying drawings, Figure 1 represents an obverse view of a handle, illustrating a portion of my new design; and Fig. 2 represents a reverse view of a handle, illustrating the remaining portion of my new design.

The leading features of my new and original design as to the obverse side of the handle are as follows:—the combined foliate and scroll ornamentation extending diagonally across the handle at or about the middle portion thereof; the inclined and substantially parallel beads across the face of the handle immediately above said combined foliate and scroll pattern; the reversely placed combined foliate and scroll patterns leading toward the edges of the handle and surmounting said beads; and the inwardly leading foliate patterns immediately above the last mentioned patterns and surrounding the edges and head of the handle and inclosing a perfectly plain space, which latter is bounded by said inclined beads and by said reversely placed patterns and the patterns which surmount the latter.

The leading features of my new and original design as to the reverse side of the handle are as follows:—the combined foliate and scroll pattern extending diagonally across the handle at or about the middle portion thereof; the irregularly shaped combined foliate and scroll patterns extending from said middle

portion around the edges and head of the handle; and the perfectly plain space at the upper portion of the handle and bounded by the 45 ornate features just described.

In the accompanying drawings 1 is the handle, and, referring to the obverse side, 2 is the combined foliate and scroll ornamentation extending diagonally across the handle at or about the middle portion thereof; 3, the inclined and substantially parallel beads across the face of the handle immediately above said combined foliate and scroll patterns; 4, the 55 reversely placed combined foliate and scroll patterns leading toward the edges of the handle and surmounting said beads; 5, the inwardly leading foliate pattern surrounding the edges and head of the handle, and 6 is the 60 perfectly plain space inclosed by said inclined beads and by said reversely placed patterns and the patterns which surmount the latter.

Referring to the reverse side of the handle, 7 is the combined foliate and scroll patterns 65 extending diagonally across the handle at or about the middle portion thereof; 8, the irregularly shaped combined foliate and scroll patterns extending from said middle portion around the edges and head of the handle, and 70 9 is the perfectly plain space at the upper portion of the handle and bounded by the ornate features just described.

I claim—

The design for the handle of a spoon, substantially as herein shown and described.

In testimony whereof I affix my signature in presence of two witnesses.

FREDERICK E. PRÉTAT.
